CLAIM

The ornamental design for a foldable table, book rest
and light combination, substantially as shown and de-
scribed.

DESCRIPTION

FIG. 1 is a perspective view of a foldable table, book
rest and light combination showing my new design;
FIG. 2 is a left side elevational view thereof;
FIG. 3 is a front elevational view thereof;
FIG. 4 is a top plan view thereof; and
FIG. 5 is a top perspective view in folded condition.
